UNITED STATES PATENT OFFICE.

JAMES C. MICHIE, OF NEWPORT NEWS, VIRGINIA.

COMPOUND TOOL.

1,246,768.

Specification of Letters Patent. Patented Nov. 13, 1917.

Application filed November 21, 1916. Serial No. 132,574.

To all whom it may concern:

Be it known that I, JAMES C. MICHIE, a citizen of the United States, residing at Newport News, in the county of Warwick 5 and State of Virginia, have invented certain new and useful Improvements in Compound Tools; and I do hereby declare the following to be a full, clear, and exact description of the invention, such as will enable others 10 skilled in the art to which it appertains to make and use the same.

This invention relates to new and useful improvements in compound tools and the principal object of the invention is to provide 15 a device combining a square, try-square and tape line.

Another object of the invention is to provide a square having a novelly constructed butt in which the miter square is pivotally 20 mounted in order that the same may be moved to various angles with relation thereto.

A further object of the invention is to provide a butt which is adapted to hold the 25 tape line in such a position as to avoid damage thereto and which has a guide arranged thereon as a means for limiting the lateral movement of the tape line.

A still further object of the invention is 30 to provide a device having a clip for supporting a pencil in place.

With these and other objects in view the invention consists in the novel combination and arrangement of parts which will be 35 fully set forth in the following specification and accompanying drawing, in which:—

Figure 1 is a side elevation of try-square constructed in accordance with this invention.

40 Fig. 2 is a side view of the device from the opposite side of Fig. 1 and showing the pivoted blade partly opened.

Fig. 3 is a transverse sectional view on line 3—3 of Fig. 1, and

45 Fig. 4 is a fragmentary view of the butt showing the lower end thereof broken away to illustrate the method of cutting away a portion of the square to accommodate the try-square blade.

50 Referring to the drawing the numeral 1 designates as an entirety the butt of the square while the numeral 2 designates the blade thereof. The butt 1 comprises a pair of channel sections 3 and 4 which are riveted 55 to the angular body 5 of the blade 2. The lower end of this body is provided with the

angularly extending portions 6 and 7 for accommodating the miter square which will be more fully hereinafter described, and is shorter than the channel sections so that the 60 adjustable blade may be accommodated therein. Formed in the web portions of the channel sections near their outer ends are suitable openings 8 for the reception of a bolt 9 forming the pivot bolt the adjustable 65 blade designated by the numeral 10. This bolt has threaded thereon a nut 11 so that the blade may be held in various adjusted positions by tightening said nut. As shown in the drawing the blade is provided with a 70 longitudinal slot 12 through which the bolt extends and the free end of said blade is beveled as at 13 so as to engage the inner edge of the stationary blade when the device is in the position shown in Fig. 1 in order to 75 provide a miter square.

A suitable clip 14 is riveted or otherwise attached to one of the channel sections and is adapted to hold a pencil 15 in place therein, while the opposite channel section is provided with slits 16 forming a tongue 17 which is bent over and against one of the flanges to provide a guide for the tape line designated by the numeral 17 which is wound on a reel 18. A suitable spring 19 is 80 riveted to the flange opposite that provided with the guide and the free end of said spring bears against the tape line to hold the same in various adjusted positions. The outer end of said tape line is provided with a 85 pencil socket 20 while the opposite end is wound upon a spring wheel contained within the housing 18.

It will be apparent from the foregoing 90 that in use the device may be used as an ordinary square by placing the butt against a straight edge and extending the blade across the strip upon which the device is being used and when it is desired to make a miter cut, it will be seen that the device 95 is used in the same way except that the edge of the miter blade is used as the guide. Upon using the tape measure it will be evident that the same may be pulled outwardly by grasping the pencil socket and exerting 100 pull on the same and the outward movement of said pencil socket will cause the tape to pass through the guide and beneath the spring which engages and holds said tape in various positions. When it is desired to return the tape it will be evident that a slight 105 pressure is brought against the inner side

of the spring thus forcing the same free of the tape and allowing the same to return to wound position. It will also be evident that when so desired the point of the pencil may 5 be inserted in the pencil socket and the tape drawn out to the desired length thus placing the pencil in proper position for use in order that a mark may be made at the end of the tape thus insuring accurate measurement. It will also be evident that in using 10 the pencil in this manner the same will act as a handle for the tape measure.

While in the foregoing there has been shown and described the preferred embodiment of this invention, it is to be understood that such changes may be made in the combination and arrangement of parts as will fall within the spirit and scope of the 15 invention as claimed.

What is claimed is:—

A square comprising a body, a blade 20 formed integrally at one end of the body and extending angularly therefrom, channel members attached to the body on opposite sides, said body and channel members forming the butt of the square, said body having its end remote from the blade beveled to 25 form two edges inclined to its sides, a miter blade pivotally and slidably mounted between the eight portions of the channel 30 members and a bolt and nut for holding said blade in various adjusted positions.

In testimony whereof I affix my signature in presence of two witnesses.

JAMES C. MICHIE.
